UNITED STATES PATENT OFFICE

FREDERIC M. CARD, OF BRIDGEPORT, CONNECTICUT, ASSIGNOR TO THE SINGER MANUFACTURING COMPANY, OF ELIZABETH, NEW JERSEY, A CORPORATION OF NEW JERSEY

TRIMMING MECHANISM FOR SEWING MACHINES

Application filed May 1, 1931. Serial No. 534,274.

This invention relates to improvements in sewing machine trimmer mechanisms and has for its object to improve the trimmer-blade supporting and actuating mechanism disclosed in the United States patent to W. A. Neely, No. 826,596, July 24, 1906, to provide for more conveniently and accurately effecting the trimming of the lower of superposed plies of material in the operation of uniting said plies by stitching.

With the above and other objects in view, as will hereinafter appear, the invention consists in the devices, combinations, and arrangements of parts hereinafter described and claimed.

The several features of the invention and the advantages attained thereby will be readily understood from the following description of an embodiment thereof illustrated in the accompanying drawings, in which Fig. 1 is a front elevation of the bracket-arm and a portion of the work-supporting post of a sewing machine having the improved trimmer mechanism, which latter is shown partly in section. Fig. 2 is an end elevation of the trimmer mechanism, the bracket-arm and the throat-plate of the machine being shown in section. Fig. 3 is a side elevation of the edge-guide and its supporting means, as viewed from the right in Fig. 1 and also of the keeper for yieldingly holding the trimmer-blade carrier in its inoperative position. Fig. 4 is a perspective view of the edge-guide and its supporting bracket. Fig. 5 is a perspective view of the trimmer knife and its carrier. Fig. 6 is a horizontal section of the free end of the machine bracket-arm, substantially in the plane of the main-shaft journaled in said arm.

The sewing machine illustrated in the drawings has a frame including a work-supporting post 1, and a standard 2 for the usual bracket-arm 3 which terminates in a head 4 overhanging the post 1. Journaled for rotation in the bracket-arm 3 is a main-shaft 5 carrying at one end a belt-pulley 6 and at its opposite end a crank-disk 7 operatively connected by means of a link 8 with a needle-bar 9. The needle-bar 9 carries at its lower end a needle 10 and is journaled for vertical re-

ciprocation in a bushing 11 suitably fixed in the bracket-arm head 4.

Any suitable mechanism may be employed for cooperation with the needle in the formation of stitches, the work being preferably advanced by a feed-dog 12 of the lower four-motion type projected through the throat-plate 13 upon the work-supporting post in a raised portion of said throat-plate which also provides a knife-guiding shoulder 14. Opposed to the feed-dog 12 is a presser-roller 15 carried by an arm 16 of a bracket 17 secured upon the lower end of the usual spring-depressed presser-bar 18 movable endwise vertically in bushings, as 19, secured in the head 4 of the bracket-arm.

The under side of the bracket-arm 3 is formed with a flat faced boss 20 providing a seat for a trimmer-mechanism supporting bracket 21, detachably secured upon said boss and from which projects a horizontally disposed fulcrum-stud 22 pivotally supporting the shouldered hub-sleeve 23 of a vertically depending swinging frame 24. The hub-sleeve 23 is held on the fulcrum-stud by the head of a screw 22' threaded into the free end of said fulcrum-stud. The swinging frame 24 is grooved to provide a radially extending guideway 25 in which is fitted one member 26 of a two-part carrier-block, said member 26 being secured in the guideway 25 by a screw 27 for vertical adjustment toward and from the pivotal axis of the frame 24. Fixed by a screw 29 in a transverse groove in the carrier-block member 26 is a complementary carrier-block member 30 which may be adjusted upon the member 26 in the general direction of the swinging movements of the frame 24, i. e., crosswise of the guideway 25.

The carrier-block member 30 is forked at 90 its lower end to provide spaced arms 32 spanned by a fulcrum-pin 33 pivotally supporting an angular trimmer-blade holder 34, 35. In the operative position of the swinging frame 24, the arm 34 of said holder is substantially horizontal, said arm 34 carrying the shank 36 of a trimmer-knife having a depending, vertically disposed fin 37 provided with a cutting edge 38 directed oppositely to the direction of feed of the work. 100

The trimmer-knife shank 36 is slotted to receive a securing screw 39 and a steadyng pin 40, whereby the blade 37 may be adjusted toward and from the line of seam formation. 5 The other arm 35 of the trimmer-blade holder is bent upwardly at the trimmer-blade side of the carrier-block member 30 into substantial parallelism therewith and is acted upon by a spring 41 in a direction to yieldingly 10 urge the knife-fin 37 downwardly toward the throat-plate to an extent limited by the head of a screw 42, passing through a slot in the upper end of the holder-arm 35 and threaded through the member 30 to which it is ad- 15 justably secured by a lock-nut 43, the spring 41 being coiled about the shank of said screw 42 between the holder-arm 35 and the member 30.

The swinging frame 24 is releasably 20 latched to a vertically depending rock-lever 44, fulcrumed upon the swinging-frame hub 23 for vibratory movements about an axis coinciding with the axis of swinging movement of said frame 24. The rock-lever 44 is 25 connected by a link 45 with a crank-arm 46 clamped upon a horizontally disposed rock-shaft 47 journaled in bearing lugs 48 at the rear side of the machine bracket-arm 3. Secured upon the rock-shaft 47 is another 30 crank-arm 49 which is forked to straddle an eccentric 50 upon the main-shaft 5. The rock-lever 44 terminates at its lower end in a segmental guide-bracket 51 projecting from opposite sides of said rock-lever in an arc having 35 the fulcrum-axis of said rock-lever as its center of curvature, said guide-bracket 51 being preferably slidably engaged by the adjacent face of the swinging frame 24. Yieldingly projected from the swinging 40 frame 24, by a spring 53, is a latch-bar 54 slidably disposed in a socket 55 in the frame 24, said latch-bar being adapted to enter a keeper-aperture 56 in the rock-lever 44, whereby the trimmer-frame 24 may be releasably 45 locked to said rock-lever.

Means is provided for conveniently retracting the latch-bar 54 from the keeper-aperture 56. To this end, the latch-bar has a laterally extending pin 57 projecting through a 50 horizontally disposed slot 58 in the frame 24, said pin 57 entering a slot 59 in a vertically directed arm 60 of a release-lever 60, 61 fulcrumed intermediate its ends upon a pivot-screw 62 threaded into the frame 24. The de- 55 pending other arm 61 of the release-lever is widened to form a thumb-piece opposed to an adjacent finger-piece 63 extending integrally from the trimmer-frame 24. By grasping both the thumb-piece 61 and the 60 finger-piece 63, not only may the latch-bar 54 be readily disengaged from the rock-lever 44, but the frame 24 may be thereby conveniently swung forwardly beyond the latching position thereof for the purpose of manu- 65 ally trimming the lower ply margin in ad-

vance of the needle, preparatory to sharply turning the work as for instance in stitching corners. Furthermore, the opposed thumb-piece 61 and finger-piece 63 provide convenient means for swinging the unlatched frame 70 24 rearwardly out of operative position, the latch-bar 54 riding the guide-bracket 51 during movement of said frame into and out of operative position. When the frame 24 is thrown rearwardly out of operative position 75 it is held in its inoperative position by a keeper comprising a bent spring 64 which engages the elongated head of the screw 27, as shown in Figs. 2 and 3 of the drawings. In the present instance, the spring 64 is secured 80 by a screw 65 upon a collar 66 fixed upon the lower presser-bar bushing 19.

It is important to properly direct the upper 85 ply or plies of material with which the lower trimmed ply or plies are to be united by stitches, in order that said upper material 90 ply may not be marred by the trimming knife and to insure that the lower ply margin is severed along the desired line with respect to the edge of the upper ply. To this end, 95 it is customary to provide an edge-guide for the upper ply, the edge-guide provided in the present machine being particularly designed to facilitate handling of the work and being supported in a manner whereby said edge-guide may be readily thrown into and 100 out of operative position and may be conveniently adjusted with respect to the line of seam formation as well as for different thicknesses of work.

According to the present improvement, an edge-guiding fin 67 disposed closely adjacent to the needle-path depends vertically from a shank 68, bent laterally away from the line of seam formation and detachably secured upon the forwardly extending end of an arm 69 pivotally supported by a screw 70 upon a vertically disposed member 71 of an angular bracket 71, 72. The other member 72 of said bracket is secured by a screw 73 in a recessed seat provided in a supporting block 74, for horizontal adjustment of said member 72 crosswise of the line of seam formation. Integral with the supporting block 74 is a split collar 75 clamped by a screw 76 for vertical and also angular adjustment upon the lower reduced end of the needle-bar bushing 11. The rearward end of the edge-guide carrying arm 69 is rounded and is provided with spaced notches 77 and 78 110 adapted to be yieldingly engaged by a V-shaped portion of a spring 79 for holding said arm in operative and inoperative positions into which it may be swung about the screw 70. The spring 79 is suitably fixed by 115 screws 80 upon the bracket-member 71.

The present trimming mechanism, in common with that of the Neely Patent No. 826,596, has the advantage of severing the work in a direction parallel with the direc- 120 125 130

tion of feed, thereby obviating the choppy appearance of the trimmed edge resulting from employing an under-ply trimmer swinging in an arc about a vertical axis. It 5 will be understood that as the pivotal axis of the trimmer-blade carrying frame is disposed vertically above the knife blade in its work-severing position and is removed a considerable distance from said knife-blade, 10 the latter acts to sever the work in a substantially straight line.

The arrangement of the trimmer-blade carrying frame in sliding engagement with its actuating rock-lever and the elongated 15 pivot bearings therefor provide a degree of rigidity conducive to accurate performance and long wear. The adjustable yielding feature of the knife blade provides for readily accommodating materials of different thicknesses and the edge-guide supporting means 20 is of a character such as not to interfere with free handling of the work.

Having thus set forth the nature of the invention, what I claim herein is:

25 1. In a sewing machine having a frame including a work-support and a bracket-arm overhanging the work-support, stitch-forming and work-feeding mechanisms, a trimming mechanism comprising a vertically disposed rock-lever having a horizontal-axis fulcrum upon said bracket-arm, means for 30 rocking said lever, a vertically depending frame journaled coaxially with the fulcrum of and disposed adjacent to said rock-lever for swinging movements substantially parallel with the line of feed, a trimmer blade carried by said swinging frame and having a vertically disposed work-severing fin provided with a cutting edge opposed to the direction 35 of feed, and a latch releasably connecting said swinging frame and rock-lever.

2. In a sewing machine having a frame including a work-support and a bracket-arm overhanging the work-support, stitch-forming 45 and work-feeding mechanism, a trimming mechanism comprising a vertically disposed rock-lever having a horizontal axis fulcrum upon said bracket-arm, means for rocking said lever, a swinging frame journaled coaxially with the fulcrum of and disposed adjacent to said rock-lever, a trimmer-blade holder carried by said swinging frame for adjustments in directions substantially parallel with the direction of feed 55 and radially of said swinging frame, a trimmer-blade carried by said swinging frame and having a vertically disposed work-severing fin, and a latch releasably connecting said swinging frame and lever.

3. In a sewing machine having a frame including a work-support and a bracket-arm overhanging the work-support, stitch-forming and work-feeding mechanisms, a trimming mechanism comprising a vertically disposed 60 rock-lever having a horizontal-axis

fulcrum upon said bracket-arm, means for rocking said lever, a swinging frame journaled coaxially with the fulcrum of and disposed adjacent to said rock-lever, a trimmer-blade carried by said swinging frame, a latch 70 releasably connecting said swinging frame and rock-lever, a latch-operating lever pivotally mounted upon said swinging frame and having a thumb-piece, and a finger piece extension on the swinging frame opposed to 75 said thumb-piece.

4. In a sewing machine having a frame including a work-support and a bracket-arm overhanging the work-support, stitch-forming and work-feeding mechanisms, a trimming mechanism comprising a supporting bracket upon the under side of said bracket-arm and carrying a horizontally disposed fulcrum-stud, a vertically depending swinging-frame having a hub-sleeve pivotally 80 mounted upon said fulcrum-pin, a trimmer-blade carried by said swinging frame and having a vertically disposed work-severing fin, a rock-lever fulcrumed coaxially with 85 said swinging frame and depending in slid- 90 able contact with said swinging frame, means for vibrating said rock-lever, a latch releasably connecting said swinging frame and rock-lever, and means for holding said swinging frame in an inoperative position disconnected 95 from said rock-lever.

5. In a sewing machine having a frame including a work-support and a bracket-arm overhanging the work-support, stitch-forming and work-feeding mechanisms, a trimming mechanism comprising a vertically disposed swinging-frame having a horizontal axis journal upon said bracket-arm, means for swinging said frame, a trimmer-blade holder overhanging the work-support and pivotally carried by said swinging frame, a trimmer-blade carried by said holder and having a vertically disposed work-severing fin, a spring acting upon said holder to yieldingly urge said trimmer-blade fin toward 100 the work-support, and means for limiting the work-support approaching movement of the trimmer-blade fin under the action of said spring.

6. In a sewing machine having a frame including a work-support and a bracket-arm overhanging the work-support, stitch-forming and work-feeding mechanisms, a trimming mechanism comprising a vertically disposed swinging-frame having a horizontal-axis journal upon said bracket-arm, means for swinging said frame, a supporting member adjustably carried by said swinging frame, an angular trimmer-blade holder pivotally mounted intermediate its ends upon 115 said supporting member having a horizontally extending arm overhanging the work-support and its other arm substantially parallel with said holder-supporting member, a trimmer-blade having a depending work-sever- 120

125

130

ing fin carried by the horizontally disposed arm of said holder, and a spring interposed between the other holder-arm and said supporting member acting to yieldingly depress said trimmer-blade.

- 5 7. In a sewing machine having a vertically reciprocating needle and a work-feeding mechanism, the combination with a trimming mechanism including a trimmer-blade having
- 10 a depending fin provided with a cutting edge opposed to the direction of feed for trimming the under of superposed plies of material adjacent to the outer edge of the overlying ply, of means for guiding the overlying ply
- 15 of material comprising an arm carrying a depending edge-guiding fin overhanging the work-support adjacent to the path of the needle, a bracket secured upon the bracket-arm of the machine and providing a pivotal
- 20 support for said arm, and means for latching said arm in operative and inoperative positions upon said bracket.

In testimony whereof I have signed my name to this specification.
